Specification for Design.

Patented Mar. 25, 1919.

Application filed August 19, 1918. Serial No. 250,613. Term of patent 7 years.

To all whom it may concern:

Be it known that I, FREDERICK KAUPMANN, Jr., a citizen of the United States, residing at Brooklyn, county of Kings, State of New York, have invented a new, original, and ornamental Design for Hat-Pins, Scarf-Pins, Cuff-Links, Tie-Clips, Rings, Fobs, Pendants for Neck-Chains, Pins, or Articles of Manufacture of like Character, of which the following is a specification, reference being had to the accompanying drawing, forming a part thereof.

I claim:

The ornamental design for a hat pin, scarf pin, cuff link, tie clip, ring, fob, pendant for neck chains, pin, or article of manufacture of like character, as shown.

FREDERICK KAUPMANN, JR.
